INVENTOR
Bernard Stember
BY *C. J. Cottrell*
ATTORNEY

UNITED STATES PATENT OFFICE

BERNARD STEMBER, OF NEW YORK, N. Y.

POCKET

Application filed December 28, 1929. Serial No. 416,723.

This invention relates to pockets mounted on flat rigid surfaces, and maintained in a closed condition by means of hookless fasteners, or the like.

The hookless fastener, among its many applications has been extensively used to close pockets in hand bags, suit cases, clothing, etc. However, the hookless fastener is objectionable when so used as its presents a rough edge at all times to a hand entering the pocket, and it is necessary to distort the pocket to facilitate access thereto, this being due to the construction of the pocket, which usually consists in a sheet of material of substantially rectangular shape attached to a wall directly along three of its edges, the fourth edge being held to the wall by hookless fasteners.

It is an object of this invention to provide a pocket which may be expanded so that access thereto is not accompanied by distortion, and the hookless fasteners may be used to close the pocket without limiting access to the pocket.

This and other objects are attained by the novel construction, combination and arrangement of parts hereinafter described and shown in the accompanying drawing, constituting a material part of this disclosure, and in which:

Figure 1 is a plan view of a pocket embodying the invention.

Figure 2 is a sectional view of the pocket.

Figure 3 is a perspective view of a section of the pocket.

Figure 4 is a plan view of a section of a modified form of pocket.

Referring to the drawings, a substantially rigid wall 5 has mounted thereon a pocket comprising a sheet 8 of material connected with the wall by the side gussets 6 and 7, and the bottom gusset 9.

Fixed to the wall 5 is a tape 10 carrying the elements 11 of a hookless fastener, and similar tape 12 carrying the fastener elements 13 is fixed to the upper edge of sheet 8. As shown in Figs. 1 and 3, the tapes 10 and 12 are continued beyond the pocket, the portion 21 of tape 12 being attached to wall 5, and the fastener elements terminate in a stop

14, which limits the movement of the hooker 15, the latter having a tab 16 by means of which it may be manipulated.

The wall 5 may continue above the tape 10, or it may be provided with a substantially rigid extension in the form of the sheets 17 and 18 of material, attached to the wall 5 and to each other, as shown in Fig. 2, which form is applicable in connection with a pocket mounted on the inner wall of a hand bag.

In operation, the hooker is moved to the right, until it engages stop 14, (Figs. 1, 3) to disengage the elements 11 and 13 of the fastener. The gussets 6, 7, 9 then enable the pocket to be expanded to facilitate access thereto.

In Fig. 4, is shown a modified form of pocket in which the sheet 8 at one edge is attached directly to the wall 5, and the gusset 7 is omitted, the pocket being provided with a gusset 6 at the opposite end. This form of pocket may be entered with ease, but, obviously, is not as commodious as the form shown in Figures 1 and 3.

The pocket as herein described is especially adapted for use on rigid walls which extend a considerable distance above the mouth of the pocket. It is applicable in hand bags, suit cases, shoe bags supported on walls, etc., and in other situations in which one side of the pocket extends considerably above the other side.

The foregoing disclosure is to be regarded as descriptive and illustrative only, and not as restrictive or limitative of the invention, of which, obviously an embodiment may be constructed including modifications without departing from the general scope herein indicated and denoted in the appended claims.

Having thus described my invention, what I claim as new and desire to secure by Letters Patent, is:

1. A pocket, comprising a substantially rigid wall, a sheet of material, gussets connecting the side and bottom edges of the sheet to the wall, said wall extending above the upper edge of the sheet, and hookless fastener elements attached to the wall and to the upper edge of the sheet of material, said elements extending beyond one end of the pocket.

2. A pocket, comprising a wall, a sheet of material having a free edge, gussets connecting the other edges of the sheet of material to the wall, said wall extending above the free edge, and hookless fastener elements attached to the wall and the upper edge of the sheet of material, said elements extending beyond one end of the pocket.

3. A pocket, comprising a wall, a sheet of material having a free edge, gussets connecting the side edges of the sheet to the wall, means for connecting the bottom edge of the sheet to the wall, said wall extending above the free edge, and hookless fastener elements attached to the wall and the upper edge of the sheet of material, said elements extending beyond one end of the pocket.

In testimony whereof I affix my signature.
BERNARD STEMBER.
